UNITED STATES PATENT OFFICE.

NILS D. LEVIN, OF COLUMBUS, OHIO, ASSIGNOR TO THE JEFFREY MANUFACTURING COMPANY, OF COLUMBUS, OHIO, A CORPORATION OF OHIO.

COAL-MINING MACHINE.

Application filed October 7, 1918, Serial No. 257,158. Renewed June 4, 1926.

The present invention relates to certain new and useful improvements in coal mining machines, and particularly to the class of machines having cutting mechanism adapted to form a kerf below a section of the mine wall, breaking down mechanism adapted to dislodge the material above said kerf, and conveying devices arranged to enter said kerf to receive the dislodged material and remove it rearwardly of the machine.

The especial object of this invention is to provide, in a machine of the class described, means for reclaiming the slack produced by the cutting mechanism and to deposit it in the conveyer for transportation rearwardly of the machine.

The devices by which I attain this object are fully set forth in the following specification and illustrated in the accompanying drawings of which

Figs. 1 and 2 constitute a general plan view of the preferred embodiment of my invention.

Figs. 3 and 4 constitute a side elevation 25 of the machine illustrated in Figs. 1 and 2.

Fig. 5 is a section along the line 5—5 of Fig. 3.

Fig. 6 is a section along the line 6—6 of Figs. 1 and 5.

Fig. 7 is a section along the line 7—7 of Figs. 1 and 2.

Fig. 8 is a section along the line 8—8 of Fig. 2.

Fig. 9 is a section along the line 9—9 of Fig. 2.

Fig. 10 is a section along the line 10—10 of Fig. 2.

Fig. 11 is a side elevation of the machine illustrating its operation.

Fig. 12 is a detail of the apron supporting hinge.

Fig. 13 is a general plan view of the machine illustrating its relation to the material to be mined.

Fig. 14 is a fragmentary plan view illustrating the operation of the machine.

Like numerals refer to similar parts in the several figures.

Speaking broadly this machine comprises a bottom pan adapted to rest upon and slide in any direction over the floor of the mine and to be anchored in fixed relation to the coal face during the operation of the machine. Upon the bottom pan is mounted

a turn table adapted to rotation in either 55 direction, and constituting the main frame upon which the operative parts of the machine are mounted. These operative parts constitute a cutting mechanism adapted to form a kerf above, behind, and below a 60 section of the coal vein, breaking down and gathering devices by which fragments of the coal are broken off from the partially severed section and transferred to the loading devices by which said fragments are 65 deposited in conveniently placed cars for transportation from the mine, and power devices by which the several elements of the machine are actuated. In the drawings the numeral 1 indicates, as an entirety, the bottom pan which is adapted to rest directly 70 upon the floor of the mine. This pan consists of a rectangular steel plate the edges of which are turned upward as indicated at 2, to facilitate its sliding in any direction over the floor of the mine. The plate 1 is stiffened by longitudinally extending steel bars 3 and by an angular angle bar 4 all of which are electrically welded to the surface of the plate. At its forward end the 75 plate 1 is semi circular in form and the angular stiffening angle 4 is positioned adjacent and concentric with this end of the plate. Concentric with the annular bar 4 is a pivot bearing 5 which engages the 80 downwardly projecting pivot post 6 of the main frame casting 7 to prevent its lateral displacement relative to the pan. Attached to the plate 1 in a concentric circle outside of the stiffening angle 4 is a plurality of bearing brackets 8 in which are mounted anti-friction bearing rollers 9. The main frame casting 7 is supported directly upon these rollers 9 and constitutes a turn table, adapted to rotation in either direction, upon which 90 the operative parts of the machine are mounted.

Attached to the main frame 7 is an electric motor 10 arranged to actuate the machine, and I have indicated at 11 a controlling mechanism, having an operating handle 12 convenient to the hand of the operator, by which the motor may be controlled. The motor 10 is connected with the controller 11, and also with any convenient source of 100 electric power, by suitable electric conductors which are not shown in the drawings as they form no part in the present invention.

tion and are well understood by persons skilled in the art. For purposes of illustration I have shown an electric motor, but it is to be borne in mind that any type of motor may be employed which is suitable to the conditions under which the machine operates.

Formed on the motor 10 are journal bearings 13 in which are mounted the trunnions 14 and 15 of a cradle casting 16 upon which is carried the cutting mechanism and the gathering mechanism of the machine, as will hereinafter appear. Journalized in a bearing formed in the trunnion 15 and in a second bearing 17 supported on a pedestal of the main frame 7, is a transverse power shaft 18 from which the several elements of the machine are actuated and which is itself driven from the motor 10 through the spur gear 19 and the armature pinion 20.

The cutting mechanism comprises a vertically disposed loop shaped cutter frame 21 upon which travels an endless cutter chain 22 having renewable cutter bits 23 adapted to cut a kerf in the coal body above, behind, and below a section of the mine wall to entirely sever it from the mass of the vein. The cutter chain 22 is of the type well known in the mining machine art, consisting of alternate strap and block links, and is engaged by a sprocket wheel 24, mounted upon the power shaft 18. Upon the hub of this sprocket wheel 24 is formed clutch teeth 25 adapted to engage with similar teeth of the clutch member 26 splined to the shaft in a manner common to such clutches.

The cutter frame 21 is formed of a steel bar 27, of rectangular cross section, to the sides of which are attached the plates 28 the projecting edges of which form the guide ways in which the chain 22 travels. The rectangular bar 27 is bent to form a loop and is secured at both ends to the vertical plate 29 which is attached to a flange of the cradle casting 16. In order to facilitate handling the machine in the mine the vertical width of the cutter frame 21 is made less than the total height of the coal vein which is to be removed, and this cutter frame is adapted to rotary movement about the trunnions 14 and 15 and is so formed that when in its upper position of adjustment the upper side 30 of the loop will be parallel with the general direction of the coal seam at the line of the roof of the mine, to remove the upper portion of the coal vein, and when in its lower position the lower side 31 of the loop will be parallel with the general direction of the coal seam at the line of the floor of the mine, to remove the lower portion of the vein. When the mining machine is placed adjacent the coal face, and the turn table is rotated in the direction to cause the cutter bits 23 to engage the coal face, there will be formed a loop

shaped kerf extending above, behind, and below a section of the coal, entirely severing said section from the body of the vein. However, due to the natural cleavage crevices of the coal, the material of this severed section breaks down in smaller fragments of suitable size to be handled by the loading mechanism. It is commonly preferable, at the beginning of each cycle of operation, to adjust the cutting mechanism to its upper position, as illustrated in Fig. 15, and remove a section from the upper portion of the mine wall, after which the cutting mechanism may be rotated on the trunnions 14 and 15 to its lower position of adjustment, as illustrated in Fig. 4, and the remainder of the vein be removed. The vertical adjustment of this cutter frame 21 may be accomplished in any preferred manner. In the drawings I have illustrated a hydraulic jack 32 connected to the main frame casting 7 at 33 and to the cradle casting 16 at 34. A pump 35, actuated by an eccentric 36 attached to the power shaft 18, supplies the pressure to actuate this jack. As these devices form no part of the present invention further description of them is not thought to be required at this time.

The loading mechanism comprises a receiving conveyer having a forward portion extending parallel with and in the same horizontal plane as the lower side of the cutter frame, in position to enter the kerf formed thereby and to receive the coal as it is severed from the body of the vein, and a rearward portion inclined upwardly to discharge said severed material into a loading conveyer by which it is delivered to cars conveniently placed upon the tracks at the rear of the machine.

The receiving conveyer is of a well known type having an endless chain 37 adapted to travel in guide ways 38 and 39 and having laterally extending flights 40 adapted to engage the coal to move it along a suitable trough 41. Formed on the conveyer flights 40 are upwardly extending sockets 40' in which are secured renewable pick pointed bits 40'' which extend upwardly above the upper bounding plane of the cutter bits 23. At the sides of the room, where the depth of the undercut is relatively shallow, the natural cleavage of the coal may be depended upon to break it down. Towards the center of the room, however, the overhanging column of coal attains such thickness that it sometimes fails to break off. Under such circumstances, when the overhanging mass attains a sufficient length, its undersurface will be engaged by the bits 40'' which exert a tearing strain thereon, tending to pry off fragments from the partly severed body and insure the dislodgment of the coal in fragments of convenient size for transportation. The guide ways 38 and 39 are formed of

suitable structural material and constitute the supporting frame work of the conveyer. At the rearward end of this conveyer is mounted in suitable bearings a vertical shaft 42 to which is attached the sprocket wheel 43 which engages the conveyer chain 37 to drive it. The vertical shaft 42 is connected through suitable gearing with the power shaft 18 to actuate the conveyer but as these devices form no part in the present invention description of them is not thought to be required at this time. At the forward end of the conveyer is a forwardly and laterally extending plate 44 which affords a sliding support for the conveyer flights 40 and which is continued rearwardly as the bottom of the trough 41. The plate 44 is extended laterally towards the cutter bar 31 and constitutes the apron upon which the coal is received as it is dislodged from the body of the vein. Along the advancing edge of the apron 44 are downwardly projecting lugs 45 which engage the flange 46 of the cutter arm to support the apron and maintain its operative relation with the cutter bar 31. Material received upon the apron 44 will be engaged by the flights 40, carried rearwardly of the machine and delivered into a loading conveyer 47 which is pivotally mounted upon a circular extension 48 of the main frame casting 7. This loading conveyer is arranged to deliver material received from the gathering conveyer to the car 49 suitably placed upon the mine tracks 50 at the rear of the machine. As the details of construction of these conveyers form no part in the present invention further description of them at this time is not thought to be required.

The feeding mechanism by which the machine may be moved bodily relative to the material to be mined, and by which the main frame casting 7 may be rotated relative to the pan 1 to cause the cutter bits 23 to engage the coal to cut it, comprises a winding drum 51 and a feed rope 52 windable thereon. The feed rope 52 is provided at its free end with a terminal 53 adapted to convenient attachment to the abutment 54 upon the pan 1 or to other suitable anchorage, and guide sheaves 55, 56 and 57 are provided upon the turn table to guide the rope 52 in any desired direction. As shown in Fig. 6 the winding drum 51 is mounted upon a vertical shaft 58 journaled in suitable bearings 59 of the main frame casting. Connected with the body of the drum 51 is a suitable friction clutch of well known construction, adapted to be controlled by a hand wheel 60 to connect the said drum with the vertical shaft 58. Attached to the lower end of the vertical shaft 58 is a worm gear 61 in engagement with a worm 62 mounted upon a transverse shaft 63 which is journaled in suitable bearings 64 and 65 as shown in Fig.

5. Fixed to the shaft 63 is a ratchet wheel 66 engaged by a pawl 67 carried by the ratchet lever 68 which is oscillatable about the shaft 63. The lever 68 is connected by an eccentric rod 69 with an eccentric 70 attached to the power shaft 18. By the rotation of the eccentric 70 the ratchet lever 68 is caused to oscillate thereby rotating the ratchet wheel 66 and through the worm gear 61 and 62 the winding drum 51. Suitable anchoring devices of any preferred construction may be used to hold the machine to its work during the cutting operation. For purposes of illustration I have shown at 71 and 72 arms which are hinged to the bottom pan 1 and which are adapted to extend laterally of the machine and to be secured in place by jack posts 73. As these devices form no part in the present invention description of them is not thought to be required at this time.

After the completion of each cycle of operation the cutter frame 21 will be moved to the right hand side of the machine, as illustrated in Fig. 13, and raised to the upper position of vertical adjustment. The anchoring devices 73 will be released, the feed rope 52 passed around the guide sheave 56 and attached to a suitable anchor jack 74 positioned adjacent the coal face on the center line of the working. When the winding drum is actuated the rope 52 will be wound to draw the machine bodily forward into position to begin the next cycle of operation. The anchoring devices 74 are then adjusted to hold the sub base 1 in position during the cutting operation and the feed rope passed around the guide sheave 55 and 56 and connected to the abutment 54 on the sub base 1 as illustrated in Fig. 3 and 14. When now the cutting mechanism is actuated and the feed rope 52 is wound upon the drum 51 the cutter bits 23 will be forced into contact with the coal body to form a kerf above, behind and below a crescent shaped section of coal to completely sever it from the mine wall. The cuttings produced by the cutter bits 23 will be carried inwardly above said coal section, downwardly behind and outwardly beneath it to be discharged upon the floor of the mine. The volume of this fine coal is such that if allowed to accumulate along the coal face it would seriously interfere with the operation of the machine. Heretofore it has been the practice to shovel this accumulation of cuttings away from the path of the machine, entailing a large amount of arduous labor, and I have provided the hereinafter described slack reclaiming conveyer with a view to the elimination of such labor and the conservation of a large amount of valuable material.

Surrounding the cutter frame 21 near its rearward end is the slack reclaiming con-

veyer comprising an endless conduit 75 formed of suitable structural steel material and attached to the cutter frame by suitable attachment angles 76 and 77. The conduit 75 is of generally rectangular cross section and has a lower horizontal run 78 extending across and beneath the cutter frame in position to contact with the floor of the mine when the cutter frame is in its lowest position of vertical adjustment. The conduit 75 also has an ascending leg 79 at the receding side of the cutter frame adjacent the trough 41 of the gathering conveyer, a horizontal run 80 above the cutter frame, and a vertically descending leg 81 at the advancing side of the cutter frame. The ascending and descending legs of the conduit together with the upper horizontal run are completely enclosed while the lower horizontal run is open along its forward side and is inclined to the longitudinal lines of the cutter frame in such manner as to present an open front in the direction of its advance through which the slack coal may be gathered from the floor of the mine. An endless chain 82 is arranged to travel in guide ways 83 of the conduit and to this chain are attached laterally extending scraper flights 84 adapted to engage material in the lower horizontal run 78 and convey it upwardly through the leg 79. Near the upper end of the leg 79 there is provided a window 85 having a discharge lip 86 along its lower edge over which this material is discharged. The conduit is curved outwardly at this discharge point to overhang the trough 41 of the gathering conveyer, and the flights 84 are inclined forwardly in the direction of the chain 82 to insure perfect discharge. Positioned at the upper advancing corner of the conduit is a sprocket wheel 87 which engages the conveyer chain 82 to drive it. This sprocket wheel 87 is attached to the forward end of a shaft 88 which is journaled in a suitable bearing 89 attached to the plates of the conduit. Attached to the rearward end of the shaft 88 is a bevel gear 90 which meshes with a similar gear 91 attached to the shaft 92 supported in a suitable bearing 93 of the machine frame. A sprocket wheel 94 is mounted upon the shaft 92 and is connected through an endless driving chain 95 with the sprocket wheel 96 fixed to the end of the power shaft 18. A suitable friction clutch 97 is arranged to connect the shaft 92 with the sprocket wheel 94 to control the actuation of the slack conveyer. While the cutting mechanism is operating to remove the lower section of the coal vein the cutter bits 23 will drag the slack from the kerf over the floor of the mine into position to be gathered by the bottom plate 98 of the advancing slack conveyer, and I have provided an adjustable apron which may be moved into position during the removal of

the upper section of coal to receive said cuttings and conduct them to the slack conveyer.

Attached to the conduit 75 is a bracket 99 having a hinge pin 100 upon which is mounted a hinge block 101. Projecting outwardly from the hinge block 101 is a shaft 102 adapted to rotation about the hinge pin 100 in a plane of the lower side 31 of the cutter frame. Mounted upon the shaft 102 are two collars 103 and 104 which are rigidly secured to a steel plate 105 thereby adapting it to rotation about the said shaft. The proportions of the parts above described are such that the plate 105 may lie in the same plane with and form an extension of the bottom plate 98 of the conveyer conduit. An overlapping lip 106 along the rearward edge of the plate 105 is adapted to bear upon the upper surface of the plate 98 to maintain such relation between these plates. A stud shaft 107 extends downwardly from the collar 104, perpendicular to the plate 105, and upon this stud is mounted a sleeve 108 attached to a steel plate 109 which is thus supported for rotation thereon immediately below and in contact with the plate 105. The plate 109 is curved along its forward edge and is of such proportions that it may be rotated upon the stud 107 to contact with the coal face in the vertical plane of the cutter bits at any part of the rotation of the cutter frame during the cutting operation. The plates 105 and 109, when thus positioned, constitute an apron upon which the cuttings will be received as they issue from the kerf and along which they will be drawn by the cutter bits 23 into the path of the scrapers 84. At the beginning of the cutting operation the plate 109 will be turned to its position of extreme extension, as illustrated in Fig. 13. As the cutter frame travels about the pivot of the turn table towards the center of the room, the plate 109 will bear against the face of the coal and will be pressed rearwardly until it occupies the position illustrated in Fig. 2. As further rotation of the cutter frame increases the distance from the stud shaft 107 to the coal face, the plate 109 must be rotated forwardly to maintain its contact with the coal face and I have provided at 110 a handle by which the operator may manually rotate the plate 109 to preserve such contact. Owing to the curvature and proportions of the plate 109 this contact with the face of the coal will always be in the vertical plane of the cutter bits thereby insuring the reception of the cuttings by the apron.

As the plates 105 and 109 and their supporting parts occupy positions below the cutter frame during the removal of the upper section of the coal, it is apparent that they must be removed from such position before adjusting the cutting mechanism to

remove the lower section. Preparatory to removing the lower section of coal the plates 105 and 109 are rotated upon the shaft 102 so as to lie in vertical planes, and the supporting shaft 102 is rotated upon the hinge pin 100 to incline rearwardly in advance of the cutting mechanism as illustrated in Fig. 14. The plate 109 is thus adapted to contact along its lower edge with the floor of the mine and to act as a scraper to guide fragments of loose material along the floor of the mine into the path of the slack conveyer by which they will be reclaimed and loaded into the gathering conveyer for removal from the mine.

15 What I claim is:

1. In a machine of the class described, the combination of a kerf cutter adapted to form a kerf in the mine wall at the level of or spaced above the mine floor, and means to gather the cuttings produced by the kerf cutter from the floor when operating at the floor level or from the mouth of the kerf when operating above the floor level.

25 2. In a machine of a class described, the combination of a vertically adjustable kerf cutter adapted to form a kerf in the mine wall at the level of or spaced above the mine floor, and means to gather the cuttings produced by said kerf cutter from the floor of the mine when operating at the level of the floor or from the mouth of the kerf when operating above the floor level.

3. In a machine of the class described, the combination of a vertically adjustable kerf cutter adapted to form a kerf in a mine wall at the level of or spaced above the mine floor, a simultaneously acting conveyer adapted to gather the cuttings produced by the kerf cutter from the floor of the mine when operating at the floor level, and means to convey said cuttings to said conveyer when operating above said floor level.

4. In a machine of the class described, the combination of a vertically adjustable kerf cutter adapted to form a kerf in a mine wall at the level of or spaced above the mine floor, a simultaneously acting conveyer adapted to gather the cuttings produced by said kerf cutter from the floor of the mine when operating at the floor level, and means adapted to cooperate with said kerf cutter to convey said cuttings from the kerf to said conveyer when operating above the floor level.

5. In a machine of the class described, the combination of a vertically adjustable kerf cutter adapted to form a kerf in a mine wall at the level of or spaced above the mine floor, a simultaneously acting conveyer adapted to gather the cuttings produced by the kerf cutter from the mine floor while operating at the floor level, and an adjustable apron adapted to cooperate with the

kerf cutter to convey said cuttings from the 65 kerf to said conveyer when operating above the floor level.

6. In a machine of the class described, the combination of a kerf cutter adapted to lateral movement to form a kerf in the mine 70 wall, means to dislodge the material above said kerf, a conveyer adapted to enter said kerf to receive and remove the material as it is dislodged, and means to reclaim the cuttings produced by the kerf cutter and deposit 75 them in said conveyer.

7. In a machine of the class described, the combination of a vertically adjustable kerf cutter adapted to lateral movement to form 80 a kerf in the coal body at the level of or spaced above the mine floor, means to dislodge the material above the kerf, a conveyer adapted to follow the kerf cutter into the kerf to receive and remove the material as it is dislodged, and an auxiliary conveyer 85 adapted to reclaim the cuttings produced by said kerf cutter from the floor of the mine during the operation at the floor level and deposit them in the first mentioned conveyer, and means to convey said cuttings from the 90 kerf to the said auxiliary conveyer during operation above the floor of the mine.

8. In a machine of the class described, the combination of a vertically adjustable kerf cutter adapted to lateral movement to form 95 a kerf in the coal body at the level of or spaced above the mine floor, means to dislodge the material above the kerf, a conveyer adapted to follow the kerf cutter into the kerf to receive and remove the material 100 as it is dislodged, and an auxiliary conveyer adapted to reclaim the cuttings produced by said kerf cutter from the floor of the mine during operation at the floor level and deposit them in the first mentioned conveyer, 105 and means cooperating with the kerf cutter to convey said cuttings from the kerf to said auxiliary conveyer during the operation above said floor level.

9. In a machine of the class described, the combination of a vertically adjustable kerf cutter adapted to lateral movement to form 110 a kerf in a coal body at the level of or spaced above the mine floor, means to dislodge the material above the kerf, a conveyer adapted to follow the kerf cutter into the kerf to receive and remove the material as it is dislodged, an auxiliary conveyer adapted to reclaim the cuttings produced by said kerf 115 cutter from the floor of the mine during the operation at the floor level and deposit them in the first mentioned conveyer, and an adjustable apron adapted to cooperate with the kerf cutter to convey said cuttings from the kerf to said auxiliary conveyer during operation above said floor level.

10. In an apparatus for mining coal, the combination with a kerf cutter having a cut-

ter chain adapted to be moved laterally along the coal face to form a kerf at the level of the mine floor, of simultaneously operable means to reclaim and remove from the mine floor the cuttings produced by said kerf cutter.

11. In an apparatus for mining coal, the combination with a kerf cutter having a cutter chain adapted to form a kerf in the mine wall at the level of the mine floor, of simultaneously operable means to reclaim and remove from the mine floor the cuttings produced by said kerf cutter.

12. In an apparatus for mining coal, the combination with a kerf cutter having a cutter chain adapted to be moved laterally along the coal face to form a kerf therein and to discharge the cuttings from said kerf upon the mine floor, of simultaneously operable means participating bodily in the movement of said cutter to reclaim and remove said cuttings from said floor.

13. In an apparatus for mining coal, the combination of a kerf cutter having a cutter chain adapted to form a kerf in the mine wall and to discharge the cuttings from said kerf upon the mine floor, simultaneously operable means to scoop said cuttings from

said floor, and means to empty said scoop means.

14. In an apparatus for mining coal, the combination with a kerf cutter adapted to be moved laterally through a coal face to form a kerf therein and to discharge the slack from said kerf upon the mine floor, of simultaneously acting slack collecting means participating bodily in the movement of said cutter, and having a slack engaging edge at the mine floor angularly disposed to the longitudinal line of the cutter at the mouth of the kerf.

15. In an apparatus for mining coal, the combination with a kerf cutter adapted to be moved laterally through a coal face to form a kerf therein and to discharge the slack from said kerf upon the mine floor, of simultaneously acting slack collecting means participating bodily in the movement of said cutter, said collecting means comprising a scoop having a slack engaging edge at the mine floor angularly disposed to the longitudinal line of the cutter at the mouth of the kerf, and means to empty said scoop.

In testimony whereof I affix my signature.

NILS D. LEVIN.

CERTIFICATE OF CORRECTION

Patent No. 1,656,524.

Granted January 17, 1928, to

NILS D. LEVIN.

It is hereby certified that error appears in the printed specification of the above numbered patent requiring correction as follows: Page 1, line 78, for the word "angular" read "annular"; and that the said Letters Patent should be read with this correction therein that the same may conform to the record of the case in the Patent Office.

Signed and sealed this 21st day of February, A. D. 1928.

Seal.

M. J. Moore,
Acting Commissioner of Patents.
